Primary Examiner — Ralf Seifert*(74) Attorney, Agent, or Firm* — Sheridan Ross P.C.(57) **CLAIM**

The ornamental design for a pump station base, as shown and described.

DESCRIPTION

FIG. 1 is a perspective view of the pump station base; FIG. 2 is a front elevation view thereof; FIG. 3 is a rear elevation view thereof; FIG. 4 is a left elevation view thereof; FIG. 5 is a right elevation view thereof; FIG. 6 is a top plan view thereof; FIG. 7 is a bottom plan view thereof; FIG. 8 is a perspective view of the pump station base showing the second embodiment of my new design; FIG. 9 is a front elevation view of the embodiment of FIG. 8; FIG. 10 is a rear elevation view of the embodiment of FIG. 8; FIG. 11 is a left elevation view of the embodiment of FIG. 8; FIG. 12 is a right elevation view of the embodiment of FIG. 8; FIG. 13 is a top plan view of the embodiment of FIG. 8; and, FIG. 14 is a bottom plan view of the embodiment of FIG. 8. The broken lines showing a pump station base form environment structure or boundaries that form no part of the claimed design.

1 Claim, 8 Drawing Sheets(56)
